UNITED STATES PATENT OFFICE.

PETER G. MOHR, OF BUFFALO, NEW YORK.

DESIGN FOR A CARD.

SPECIFICATION forming part of Design No. 22,695, dated August 15, 1893.

Application filed April 20, 1893. Serial No. 471,219. Term of patent 7 years.

To all whom it may concern:

Be it known that I, PETER G. MOHR, a citizen of the United States, residing in Buffalo, in the county of Erie and State of New York, 5 have invented and produced a new and original Design for Cards, of which the following is a specification.

My invention relates to a design for a card.

The design consists of a circular disk 1, in 10 the center, surrounded by a ring 2 of a darker shade and having on the outside of said ring a surrounding series of radiating pointed projections 3, with a smaller projecting pointed

portion between each projecting point 3. The three parts 1, 2 and 3 are the prominent features of my design and are of a different shade or color so that they are instantly and clearly distinguishable from each other. 15

I claim as my invention—

The design for a business card, substantially as herein shown and described. 20

PETER G. MOHR.
